DESIGN FOR A DISPLAY RACK

Pat Booher, Ashland, Ky.

Application October 22, 1941, Serial No. 103,865

Term of patent 3½ years

To all whom it may concern:

Be it known that I, Pat Booher, a citizen of the United States, residing at Ashland, in the county of Boyd and State of Kentucky, have invented a new, original, and ornamental Design for a Display Rack, of which the following is a specification, reference being had to the accompanying drawing, forming part thereof.

Fig. 1 is a front elevational view of a display rack showing my design;

Fig. 2 is a side elevational view; and

Fig. 3 is a top plan view thereof.

I claim:

The ornamental design for a display rack, as shown.

PAT BOOHER.
